UNITED STATES PATENT OFFICE.

ALONZO C. MATHER, OF CHICAGO, ILLINOIS.

STOCK-CAR.

SPECIFICATION forming part of Letters Patent No. 396,100, dated January 15, 1889.

Application filed January 18, 1888. Serial No. 261,109. (No model.)

To all whom it may concern:

Be it known that I, ALONZO C. MATHER, a citizen of the United States, residing at Chicago, in the county of Cook and State of Illinois, have invented certain new and useful Improvements in Stock-Cars, of which the following, in connection with the accompanying drawings, is a specification.

In the drawings, Figure 1 is a side elevation, partly in section, of a portion of a stock-car embodying my invention and improvements. Fig. 2 is a cross-section taken on the line $x-x$ of Fig. 1. Fig. 3 is a sectional detail showing, upon an enlarged scale, the manner of temporarily locking the stall bars or rails in place. Fig. 4 is a detail of one of the stall-bars. Fig. 5 is a sectional detail, enlarged, and showing the construction of and mode of applying the water-troughs and overflow-drains. Fig. 6 is a plan view of Fig. 5. Fig. 7 is an enlarged detail of the feed-rack, showing construction applied in the doorways of the car. Fig. 8 is a detail showing method of supplying water to the troughs. Fig. 9 is an enlarged detail taken on the line $x'-x'$ of Fig. 8, showing the branches of the feed-pipe to the troughs. Fig. 10 is an enlarged plan detail of the roof of one end of the car, showing the construction and method of locking the roof-doors securely to prevent tampering with contents of the chamber under the said doors. Fig. 11 is a cross-section taken on the line $y-y$ of Fig. 10, viewed in the direction indicated by the arrow there shown. Fig. 12 is a detail side elevation of the car, showing doorway with the door of the car pulled back, showing construction of feed-racks for said doorways. Fig. 13 is a plan detail of the car, showing location of the troughs and means of supplying the same with water.

Like letters of reference indicate like parts throughout the drawings.

A represents a stock-car, which, with the exceptions hereinafter referred to, may be made in the usual manner.

B is a central longitudinal beam extending from end to end of the car, and placed a short distance below the roof of the car. This beam B is the upper support for the boards $a-a$, the lower ends of the said boards resting on cross-beams C', supported by longitudinal beams

C C, all constructed to form the chamber D for storing hay or fodder, the said chamber having suitable siding and end walls. This storage-chamber D has the bottom sloping downwardly from the central portion toward the sides of the car and made narrower than said car, leaving openings D⁴ D⁴.

On the top of the car, extending from end to end, is an opening, D', into the chamber D. This opening is closed by a series of doors, D² D², hinged at D³. I slightly incline the doors, as shown in the drawings, so that they will shed water, to prevent contents of the chamber D from becoming wet. These doors also answer and are used as the walking-board by the brakeman or attendant of the car. I have suitable means for locking the doors all at the same time when they are closed down.

a' is a rod extending from end to end of the car and placed underneath the doors D² D² and along one side of the opening D'.

On each of the doors D², extending from the under side of the same, I have staples a^2 a^2 , and below said staples a^3 a^3 , rigidly attached to the rod a' , I have hooks a^3 a^3 . On the outside, at one end of the car, (see Fig. 10,) I bend the rod a' to form a handle or lever, as shown at a^6 , and bend on the end an eye, a^7 .

a^8 is a staple fastened to the car A, and a^9 is a padlock attached to the car A by means of a chain, a^{10} , to prevent the same from being lost.

E are feed-racks placed on each side and extending from end to end of the car A. These racks are made in sections, that they may fold between the cross-beams C' C', and also be more conveniently handled. These racks E E consist of frame-like structures, in which are bars or rounds $e-e$. These racks E E are hinged in any suitable manner at their lower ends, at $c-c$, the manner shown in drawings being most preferable. I have suitable hooks, $c'-c'$, on the inside of the car A, and suitable staples, c^2 c^2 , on the racks E E for the purpose of holding the racks in a folded position against the side of the car. The section of the racks E E extending across the doorways G G of the car A (see Figs. 7 and 12) is slightly changed in the manner of folding, as will hereinafter more fully appear. I construct the rear side of said racks with a

series of chains, *ff*, which will admit of folding the rack upward, and also prevent hay and fodder contained within the rack and chamber *D* from falling through the doorway *G G* of the car when the doors of the car are opened. To fold these doorway-sections of the rack above the doorways when so desired, I have the following construction:

f' f' are vertical rods on each side of the doorway *G G*. I attach the lower ends of the racks *E E* to the rods *f' f'* by means of links *f² f²*.

f³ is a hook fastened above the doorway, and *f⁴* is a corresponding staple on the rack *E*.

F F are the water-troughs. These troughs consist of pieces of sheet metal curved as shown. *F' F'* are bolts passing through these troughs near their upper edges. At one end the bolts *F' F'* are bent to form eyes *d d* therein.

d' d' and *d² d³* are nuts run upon the other ends of the said bolts. These bolts and nuts serve to retain the curvature of the troughs.

d² d² are eyebolts passing horizontally through the sides of the car, and the eyes of these bolts interlink with the eyes *d d*, thereby connecting the troughs to the car in such a manner that the troughs may be folded up out of the way when not in use.

To raise and lower the troughs *F F* with facility, I employ the mechanism as follows: Along the outside and near the top of the car, extending from end to end, hung in suitable bearings, *g g*, I place the rods *H H*. On one end of the rods *H H*, rigidly attached thereto, are levers *H' H'*, having weighted ends *H² H²*.

I I are short levers or cranks rigidly attached to the rods *H H*.

J J are connecting-rods, the upper ends being attached to the cranks *I I* at *I'*, and the lower ends of said rods *J J* connected to supplemental rods *K K*, which are connected to the troughs *F F*.

M is a reservoir, water-tank, box, or receiver built on one end of the car in about the position shown in the drawings, and extending across the width of the car.

M⁶ is a hinged cover for the reservoir *M*. At or near the bottom of this reservoir *M*, I connect a feed-pipe, *M'*, which I bend down and extend along underneath the floor of the car *A* to the opposite end, where I connect a short upright extension, *M²*.

M³ M³ are branch pipes extending from the upright pipe *M²* to the troughs *F⁶ F⁶* on each side of the car.

M⁴ M⁴ are short feed-pipes connected to the reservoir *M* and leading to the troughs *F F*, all of which is clearly indicated in Figs. 1, 8, 9, and 13.

L L are overflow-drains (see Figs. 5 and 6) placed at intervals along the side of the car, and *L' L'* are overflow-holes, made near the upper edge of the troughs *F F* and corresponding with each drain *L*.

L² L² are drain-boards extending along the sides of the car between the drains *L' L'*, the

outer edge being inclined downward, as is clearly indicated in Figs. 2 and 5.

N N are the detachable cross-bars for dividing the interior of the car into stalls or compartments; and *O O* are vertical bars attached to the sides of the car and mortised, as indicated at *P P*. These bars *N N* are notched near their ends, as shown at *P' P'*.

P² P² are nails or screws driven into the bars *N N*, near their ends, to re-enforce the end of the notch *P'*.

To prevent the bars *N N* from being moved endwise after being arranged to form the stalls or compartments, at which time the said bars are arranged in the mortises *P P*, I employ small blocks *Q Q*, pivoted at the sides of the car by means of bolts *Q' Q'*. These blocks *Q Q*, when lowered, rest in the notches *P' P'*, and serve to hold the bars *N N* down in place in the mortises *P P*. The said blocks *Q Q* may be swung out to one side to permit the removal and placement of the said bars.

It will be perceived that I cut the notches *P' P'* in the bars *N N* slightly longer than the thickness of the blocks *Q Q*, thereby allowing spring to the bars *N N* when weight presses against the sides of them while they are locked in position, thereby preventing breaking of the bars, which would otherwise occur.

R is a box or compartment built underneath the floor of the car *A*, about the central portion thereof, for the purpose of storing away the bars *N N* compactly when not in use.

R' is a hinged door for the compartment *R*.

It will be perceived from the foregoing description, and by reference to the drawings, that my improvements are such as may be applied with facility to an ordinary slatted stock-car.

When the car is in use for conveying cattle or stock from place to place, I arrange the hay or fodder in the compartment or storage-chamber *D*, dumping or pitching it therein through the doors *D² D²*, which are opened for that purpose. The feed-racks *E E* are lowered and become filled with hay or fodder, which passes through the side openings *D⁴ D⁴*. The bulk of the hay, however, is stored in the chamber *D*; but as the bottom of this chamber is inclined, as shown at *a a*, the movement of the car during transit will cause the hay or fodder to settle and fall toward and into the openings *D⁴ D⁴*, and the racks *E E* will thus be kept supplied as long as hay or fodder remains in the chamber *D*, which will be as much as will be required for a trip of considerable duration.

To water the stock, I lower the troughs *F F* by grasping and pushing slightly on the lever *H'* of the rod *H*, which will turn the rod *H* enough to bring the center point, *I'*, outside of the rod *H*, and thus force the trough into an open position ready to be filled with water, which is done as follows: I first raise the cover *M⁶* of the reservoir *M* and fill water therein from a hose or stand-pipe, and the troughs *F F*,

situated in the half of the car nearest the reservoir, will be filled from the feed-pipes $M^1 M^4$ direct from the reservoir M . The troughs $F^6 F^6$ are filled by the water flowing from the reservoir M down through the pipe M' , up the extension M^2 , and then to the troughs $F^6 F^6$ on each side of the car through the branches $M^3 M^3$. (See Figs. 8, 9, and 13.) The highest point of the cross- T M^2 of the main feed-pipe M' is below the line of the bottom of the reservoir M , so that the water when being fed into the reservoir M will flow through the pipe M' , and the water will be forced up through the branches thereof and fill the troughs $F^6 F^6$, and when the troughs have become sufficiently filled, to prevent overflowing I have the overflow-drains $L L$ and corresponding holes $L' L'$ in the troughs $F F$ and $F^6 F^6$.

To prevent the troughs $F F$ and $F^6 F^6$ from becoming foul, I raise or close them after the stock have been sufficiently watered by grasping and pulling upon the lever H' , which will raise the troughs on one side of the car through the connecting-rods J and K , and when the center point, I' , is brought inside of the rod H the troughs $F F$ and $F^6 F^6$ will be locked in their upright or closed position, as is clearly indicated in Fig. 2, and all water remaining in the troughs will be run out and fall on the drain-boards $L^2 L^2$. As the mechanism of the troughs is alike on both sides of the car, the same operation as the one just described relates also to the troughs on the opposite side of the car. I arrange the bars N as stated, when so desired, to form stalls of suitable width and height. By folding up the feed-racks $E E$, raising the troughs $F F$ and $F^6 F^6$, and removing the bars $N N$ and storing the said bars away in the manner already described in the compartment R the car may be used as usual for any other purpose.

By employing the means already described of locking the doors $D^2 D^2$ they can all be locked and unlocked at the same time with facility by the attendant, thereby giving better protection to the contents of the chamber D .

Having thus described my invention, what I claim as new, and desire to secure by Letters Patent, is--

1. A stock-car having a continuous series of doors located centrally in and along the car-roof to form an unobstructed running board and give direct access to a feed-storage chamber located immediately beneath the car-roof, said chamber being provided with a floor of less width than the car and inclined from the center downward and outward toward openings D^2 on each side, and racks arranged below said openings along the sides of the car, substantially as described. 55

2. In a stock-car, the combination of the troughs $F F$, hinged to the sides of the car, the longitudinal rods $H H$, located along the sides of the car above said troughs and provided with levers $H' H'$ and cranks $I I$, and the jointed rods $J J$ and $K K$, connecting said cranks to the troughs, substantially as described. 65

3. In a stock-car, the combination of the troughs $F F$ and $F^6 F^6$, the reservoir M , extending across one end of the car, the main pipe M' , leading therefrom and passing beneath the car to the opposite end thereof, said pipe being provided with an upright extension, M^2 , having branches $M^3 M^3$, leading to the troughs $F^6 F^6$, and the pipes $M^4 M^4$, leading from the reservoir to the troughs $F F$, substantially as described. 75

4. In a stock-car, the combination, with the doorways $G G$ and feed-storage chamber D , of upwardly-folding racks having chains $f f$ attached to their inner sides, the rods $f' f'$ on the sides of the doorways, and the links $f^2 f^2$, 85 substantially as described.

5. The combination, in a stock-car, of the feed-racks $E E$, made in sections and arranged along each side of the car, below the chamber D , the said racks having doorway-sections, 90 with vertical guide-rods $f' f'$ and links $f^2 f^2$, for connecting the said doorway-sections to the rods $f' f'$, and a series of chains, $f f$, for forming the rear side of the said doorway-sections, arranged as shown and described, 95 and for the purposes set forth.

ALONZO C. MATHER.
